UNITED STATES PATENT OFFICE.

ANTHONY F. MACHOLD, OF PHILADELPHIA, PENNSYLVANIA.

MEDICATED FELT.

SPECIFICATION forming part of Letters Patent No. 401,189, dated April 9, 1889.

Application filed October 25, 1888. Serial No. 289,098. (No specimens.)

To all whom it may concern:

Be it known that I, ANTHONY F. MACHOLD, a citizen of the United States, and a resident of Philadelphia, in the county of Philadelphia and State of Pennsylvania, have invented a new and useful Composition of Matter for Medicinal Purposes, of which the following is a specification.

The object of my invention is to provide a composition of matter, which can be used as a cure for rheumatism, neuralgia, and diseases of a similar nature, that can readily be applied to the person thus afflicted, in the shape of clothing or bandages.

My composition consists, essentially, of the following ingredients combined in the proportions, viz: Pure lamb's wool, sixteen ounces; dog's hair, one ounce; oil of juniper-berry, one gill. These ingredients are to be combined or mixed in the following manner: The lamb's wool and dog's hair are first mixed in their rough state and then passed through a blower (such as is used for clearing wool) which extracts therefrom all the refuse matter and leaves only the fine wool and hair, which is thoroughly mixed. After this is done the mixture of wool and hair is treated or saturated with the oil of the juniper-berry. In order to more thoroughly spread the oil

diluted with water to the extent of about one gallon of water to one gill of oil, to which is added a tea-spoonful of vitriol, which causes them to mix. The mixture of wool and hair is then thoroughly saturated with the liquid and placed to dry. The water evaporates and leaves the oil clinging to the wool and hair, after which it can be made into any shape desired.

The composition, when applied to the body of a person, not only prevents it from becoming cold, but causes it to become heated. It acts upon the whole system directly by means of the blood, which conveys everywhere throughout the body the heat it receives at the surface.

Having described my invention, what I claim, and desire to secure by Letters Patent, is—

The herein-described composition of matter, consisting of lamb's wool, dog's hair, and oil of the juniper-berry, in the proportions specified.

In testimony whereof I have signed my name to this specification in the presence of two subscribing witnesses.

ANTHONY F. MACHOLD.

Witnesses:

HEW B. MACLEAN,
